ELZIE V. MOSLEY, OF CAROLEEN, NORTH CAROLINA, ASSIGNOR TO NEWTON J. JAMES
AND MARTIN R. REED, BOTH OF CAROLEEN, NORTH CAROLINA.

BATTERY FEED FOR AUTOMATIC LOOMS.

Application filed April 6, 1922. Serial No. 550,060.

To all whom it may concern:

Be it known that I, ELZIE V. MOSLEY, a citizen of the United States, residing at Caroleen, in the county of Rutherford and 5 State of North Carolina, have invented new and useful Improvements in Battery Feeds for Automatic Looms, of which the following is a specification.

This invention relates to improvements in 10 looms, wherein weft replenishing is accomplished by automatically transferring a full weft carrier or bobbin into the loom shuttle in place of the spent carrier or bobbin.

In looms of the above type, the dog that 15 revolves the mechanism or hopper is carried by the transerrer and imparts motion to the magazine upon the return stroke of the said transerrer after the latter has transferred the carrier or bobbin to the shuttle. The 20 travel of the transerrer is such as to carry the dog an appreciable distance from the teeth of the magazine ratchet gear and as the said dog strikes the said gear with considerable force, the teeth of the latter quickly 25 become worn and useless. This frequently causes the dog to miss the next tooth and results in a thin place in the woven fabric.

Further, the head of the magazine or hopper and the ratchet gear are usually made 30 integral and when the latter has become worn, the entire head must be discarded.

The present invention aims to overcome 35 these defects by providing means whereby a new ratchet gear may be positioned without removing the worn one and to provide a mechanism for co-operation with this gear which is carried and operated by the transerrer for imparting the usual step by step motion to the magazine, the action of the 40 said mechanism however being such that the dog which engages the ratchet gear will ride over the teeth of the latter, from one to another with a minimum amount of wear.

In addition, the present invention aims to 45 provide means whereby a new ratchet gear may be easily and quickly placed in position after the original gear has become worn and the mechanism for rotating the magazine easily connected to the transerrer.

With the above and other objects in view, 50 the invention further includes the following novel features and details of construction, to be hereinafter more fully described, illus-

trated in the accompanying drawings and 55 pointed out in the appended claims.

In the drawings:

Figure 1 is a horizontal sectional view showing the magazine or hopper for the weft carriers or bobbins of an automatic replenishing loom, the invention being shown 60 in position.

Figure 2 is a transverse section on the line 2—2 of Figure 1.

Figure 3 is a detail perspective view of the dog guide. 65

Figure 4 is an enlarged sectional view illustrating the manner of pivotally mounting the dog upon the guide.

Referring in detail to the drawings, 70 wherein like characters of reference denote corresponding parts, the reference character 10 indicates a disk which forms a head for the magazine or hopper which carries the weft carriers or bobbins 11. The magazine

further includes a disk 12, which is provided 75 with grooves 13 for receiving the tips of the weft carriers 11, while the butts of the latter are received within sockets 14 provided in the head 10. The magazine or hopper thus formed is mounted upon a hollow shaft 15, within which operates a spindle 16, while the head 10 has formed therewith a ratchet gear 17. The mechanism just described

forms a part of the ordinary automatic weft 80 replenishing loom and the magazine is given 85 a step by step motion to bring the weft carriers or bobbins into proper position for placing within the shuttle 18 of the loom.

This step by step motion of the magazine is effected by mechanism which is carried and 90 operated by the transerrer 19, all of which is of the usual construction and forms no part of the present invention. As the present

invention is designed for use after the ratchet gear 17 has become worn and useless, 95 the means by which this gear is rotated, is not illustrated.

Usually, when the gear 17 has become worn, it is replaced by a new gear, as the 100 failure of the rotating mechanism to engage the proper teeth causes the magazine to remain stationary, possibly for several picks of the loom. This results in a thin place in the cloth or fabric. Heretofore, in order to remedy this by replacing a new ratchet gear, 105 it has been necessary to discard both the

gear 17 and the head 10, which is found to be exceedingly expensive.

By the use of the present invention, a new gear may be placed in position for use without removing the head 10 and the gear 17 carried thereby and in order to prevent rapid wear of the new gear, a novel form of operating mechanism is provided. The new gear is indicated at 20 and is mounted upon the hub of the disk 10 and is provided with a hub or collar 21 having a groove 22. It is held in position upon the spindle by means of set screws 23. Adjustably mounted upon the transferrer 19 by means of a pivot pin 24 which passes through a slot 25, is a guide member 26. This member 26 has pivotally mounted thereon as shown at 27, a spring actuated dog 28. This dog engages the teeth of the gear 20 for the purpose of moving the magazine or hopper step by step to successively bring the weft carriers into position over the shuttle. This operation occurs through the operation of the transferrer 19 and for the purpose of guiding the dog so that it will move from tooth to tooth of the gear 20 and ride over the faces of the teeth without disengagement from the gear, the guide member 26 is provided with a yoke or arm 29 which has a sliding engagement within an annular groove 22 provided in the hub 21 of the gear 20. By means of the slot and pin connection of the guide member 26 with the transferrer 19, the said member may be accurately adjusted to insure proper operation of the dog 28, so that the objectionable hammering action between the dog and the teeth of the gear 20 is eliminated and wear upon the teeth thus materially reduced. This is an important feature in machines of this character, for in addition to saving the cost of replacing the ratchet wheel by prolonging its life, it also saves the time necessary for such replacement. A dog 32, which is pivotally mounted upon the head 10 as indicated at 33, also engages the teeth of the gear 20 so as to prevent retrograde movement.

The invention is susceptible of various changes in its form, proportions and minor details of construction and the right is herein reserved to make such changes as properly fall within the scope of the appended claims.

Having described the invention what is claimed is:—

1. The combination with a weft replenishing loom including a rotatable magazine and a transferrer for transferring the weft carriers from the magazine to the loom shuttle, of a ratchet gear secured to the magazine, a member pivotally secured to the transferrer and including an offset yoke, a dog carried by said member and engaging the ratchet gear to rotate the latter by the operation of the transferrer and a grooved hub carried by the ratchet gear for receiving the yoke to provide a guide for said member.

2. The combination with a weft replenishing loom including a rotatable magazine and a transferrer for transferring the weft carriers from the magazine to the loom shuttle, of a ratchet gear secured to the magazine, a member pivotally secured to the transferrer, a dog carried by said member and engaging the ratchet gear to rotate the latter by the operation of the transferrer and means carried by said member and engaging the hub of the ratchet gear for guiding said member.

3. The combination with a weft replenishing loom including a rotatable magazine and a transferrer for transferring the weft carriers from the magazine to the loom shuttle, of a ratchet gear secured to the magazine, a member pivotally secured to the transferrer, a dog carried by said member and engaging the ratchet gear to rotate the latter by the operation of the transferrer and adjustable means pivotally secured to the transferrer for holding the dog into engagement with the teeth of the ratchet gear.

4. The combination with a weft replenishing loom including a rotatable magazine and a transferrer for transferring the weft carriers from the magazine to the loom shuttle, of a ratchet gear secured to the magazine, a guide pivotally secured to the transferrer, a dog carried by the guide and engaging the ratchet gear to rotate the latter by the operation of the transferrer and a yoke included in the guide and slidably engaging a groove provided in the hub of the ratchet gear for holding the dog in contact with said gear.

In testimony whereof I affix my signature.
ELZIE V. MOSLEY.
